UNITED STATES PATENT OFFICE.

ALMOND L. FITCH, OF OMAHA, NEBRASKA, ASSIGNOR TO BEEBE AND RUNYAN
FURNITURE COMPANY, OF OMAHA, NEBRASKA, A CORPORATION.

DESIGN FOR A PHONOGRAPH-CABINET.

53,362.

Specification for Design.

Patented May 27, 1919.

Application filed February 17, 1919. Serial No. 277,664. Term of patent 7 years.

To all whom it may concern:

Be it known that I, ALMOND L. FITCH, a citizen of the United States, residing at Omaha, in the county of Douglas and State of Nebraska, have invented a new, original and ornamental Design for a Phonograph-Cabinet, of which the following is a specification, reference being had to the accompanying drawing, forming a part thereof.

Figure 1 is a front view of a phonograph cabinet, showing my new design. Fig. 2 is a side view of the same.

I claim:

The ornamental design for a phonograph cabinet, as shown.

In testimony whereof I have affixed my signature in presence of two witnesses.

ALMOND L. FITCH.

Witnesses:

HIRAM A. STURGES,
ARTHUR H. STURGES.
